UNITED STATES PATENT OFFICE.

FOREST CHENEY, OF CHICAGO, ILLINOIS, ASSIGNOR TO CHENEY TALKING MACHINE COMPANY, OF CHICAGO, ILLINOIS, A CORPORATION OF ILLINOIS.

SOUND BOX.

1,417,499.

Specification of Letters Patent. Patented May 30, 1922.

Application filed April 30, 1917. Serial No. 165,401.

To all whom it may concern:

Be it known that I, FOREST CHENEY, a citizen of the United States, and resident of Chicago, in the county of Cook and State 5 of Illinois, have invented certain new and useful Improvements in a Sound Box, of which the following is a specification.

My invention relates to sound reproducing machines and particularly to a novel 10 sound box for use in connection therewith.

It is desirable to maintain a balance of tone power between the higher and lower tone registers of a musical composition when it is being reproduced from a record.

15 One of the principal objects of the present invention is to so design the reproducing diaphragm with relation to the adjacent chamber that the reproduced low tones are full and resonant and the high tones clear and brilliant. The desired result is secured by forming a cavity of increasing depth from the center to the periphery of the diaphragm, the cavity being defined by a wall of the sound box at one side and the dia-

20 phragm at the other side. Preferably the desired result is secured by concaving the diaphragm and convexing the wall, although a similar result might be secured by so shaping one only of the parts.

25 I will not attempt herein to scientifically explain the reason for the increased efficiency of tone production, except to point out that the lower tones, which are formed by the slower vibrations, and which are 30 more fully developed on the outer or larger radius of the diaphragm, are enabled to set up similar vibrations within a larger body of air. The shorter vibrations, which occur nearer the center of the diaphragm, 35 should set up similar vibrations in a smaller body of air.

A further object is to provide on the opposed faces of the sound box wall and the diaphragm a plurality of sound reflectors 40 in the form of rings or ribs having an inclined approach thereto on one side. The other side being more abrupt the sound waves are thus developed in separate air chambers of larger and smaller dimensions 45 and deflected toward the center or outlet 50 from the sound box.

A further object is the provision of means for mounting the needle arm on the sound box whereby there shall be no metallic contact except at the fulcrum points. At these 55 points the fulcrum pins are fitted within suitable apertures in such manner that all wear is taken up automatically and the possibility of chatter arising from looseness and metallic contacts is avoided.

60 A still further object is to provide a loading chute by means of which the removable needles may be accurately placed in the needle holder from the rear end thereof.

65 The invention will be more readily understood by reference to the accompanying drawings in which,

Fig. 1 is a front view of a sound box constructed in accordance with my invention;

70 Fig. 2 is an enlarged sectional view through such a sound box;

Fig. 3 is a fragmentary transverse vertical view on the line 3—3 of Fig. 2, the loading chute being omitted;

75 Fig. 4 is a bottom plan view, and,

Fig. 5 is a horizontal sectional view showing a slightly modified form of diaphragm.

80 In the drawings the sound box is shown as provided with a cylindrical sleeve 10, and the casing 11. Marginal flange 12, provides means for the attachment of the ornamental cover plate 13. The plate serves also the purpose of retaining the non-metallic rings 14—15 in position, between which rings the diaphragm 16 is confined. It will be noted 85 that the space defined by the wall 17 of the sound box and the inner surface 18 of the diaphragm is of increasingly greater depth from the center to the periphery thereof.

90 As heretofore stated, this serves a useful purpose in the reproduction of the different tones. The higher tones are made more brilliant, while the lower tones are fuller and more resonant. In addition it will be noted that I have provided circular concentric ribs 19—20, on the wall and dia- 95 phragm, respectively, the ribs being so shaped as to give the appearance of stepped concentric surfaces. This construction has the advantage of developing the sound waves of the higher and lower registers in 100 larger and smaller air chambers and de-

reflecting them outwardly, or in other words, toward the opening 21 in the sound box.

The needle arm 22 is secured to the center of the diaphragm and on its lower end is fitted to the needle holder 23. The needle arm is secured in position by means of two screws 24, which engage the sound box with their threaded portions, and at their outer ends engage rubber bushings 25 seated in openings in the lateral extensions 26 of the needle arm. The bushings are provided with an intermediate peripheral flange 27, which bears at one side against the part 26 and at the other side against a flat U-shaped spring 28. The other terminal 29 of the spring lies beneath the head of the screw. The fulcrums for the needle arm comprise the pointed pins 30 seated in suitable openings in the sound box, the pointed ends of which engage with the apertures 31 within the portion 26 of the needle arm. It will be noted that the only metallic connection between the needle arm and the sound box is where the pointed pins 30 engage with the apertures. In view of the resiliency imparted by the rubber bushings the needle arm is held firmly in position and the possibility of chattering, due to wear, is avoided.

The needle holder 23 is provided with the usual clamping screw 32, the opening 33 for the needle being continuous from end to end of the holder. Rigidly secured to the cover plate 13 is the loading chute or guide 34, the lower end of which terminates a short distance above the open upper end of the needle holder. When it is desired to replace a needle the clamping screw is released, allowing the used needle to drop out, whereupon a new needle is placed in the "breech-loading" device whereby it is dropped to the proper position and may be clamped in the usual manner.

In the construction of Fig. 5 the sound reflecting surfaces are omitted. However, the diaphragm 35 and the wall 36 are so shaped as to define a space of gradually increasing depth toward the periphery of the diaphragm. Otherwise the construction is the same as that heretofore described.

It will be noted that the diaphragm and the opposed wall of the sound box are each convex with relation to a plane perpendicular to the outlet from the box and which plane intersects the space between the wall and diaphragm. There is thus formed a space which is concavo-convex. Preferably, also, the surfaces of the diaphragm and wall are provided with the opposed concentric ribs, the inner angle of inclination of which is more abrupt than the outer angle. It will be understood, of course, that while certain advantages accrue to the use of the deflecting ribs in association with a space such as described, yet either of the features may be used separately to advantage.

It will be noted also that the fulcrum bearing between the needle arm and the casing is in such form that a circular line contact is secured. This results from the employment of a conical head pin which engages with the material surrounding a parallel sided aperture.

I claim:

1. A sound box, comprising in combination, a diaphragm and an opposed wall, said diaphragm and wall being convex with relation to a plane which is perpendicular to the outlet from the box and which intersects the space between the wall and diaphragm, substantially as described. 75

2. A sound box, having a wall adjacent the diaphragm provided with a plurality of concentric ribs, the inner angle of inclination of which is abrupt whereby sound waves are deflected toward the outlet from the box, substantially as described. 80

3. In a sound box, the combination of a concentrically ribbed diaphragm and a similarly ribbed adjacent wall, the ribs being so shaped as to deflect sound waves toward the outlet from the box, substantially as described. 90

4. In a sound box, the combination of a diaphragm, and an opposed wall, said wall and diaphragm defining a space, and concentric sound deflecting ribs on said diaphragm and said wall so shaped as to deflect sound waves toward the outlet from the box, substantially as described. 95

5. In a sound box, in combination, a needle arm, a holding connection between the arm and the box including a fulcrum having line contact with one of said members. 100

6. In a sound box, the combination of a needle arm having a fulcrum on said box, said fulcrum including a conical pin adapted to engage at a point in its perimeter with the material surrounding an opening whereby a circular line contact is secured, substantially as described. 105

7. In a sound box, the combination of a needle arm having a fulcrum bearing on said box, a holding connection, said connection including a screw rigidly engaging one member and resiliently spaced from the other member through a rubber bushing, and spring means interposed between the head of the screw and bushing, substantially as described. 115

8. In a sound box, the combination of a ribbed diaphragm and a similarly ribbed adjacent wall, the ribs being so shaped as to provide for a series of graduated concentric air chambers between said diaphragm and wall and to deflect sound waves toward the outlet from the box, substantially as described. 120

9. In a sound box, the combination of a ribbed diaphragm and a similarly ribbed adjacent wall, said wall and diaphragm de- 125

fining a series of air chambers of progressively increasing depth, substantially as described.

10. In a sound box, the combination of a
5 needle arm spaced from and having a ful-
crum bearing on said sound box, a holding
connection, said connection including a screw
rigidly engaging the box and resiliently
spaced from the arm through a rubber bush-

ing carried in the latter, and spring means 10
interposed between the screw and bushing
and spaced from the arm by the bushing.

Signed at Chicago, Illinois, this 16th day
of April, A. D. 1917.
